VEHICLE MAINTENANCE STICKER

Henry B. Simpson, Joliet, Ill.

Application June 22, 1955, Serial No. 517,151

3. Claims. (Cl. 281—16)

This invention relates in general to a device for maintaining data records, and more particularly to a vehicle maintenance sticker.

An object of my invention is to provide an improved vehicle maintenance sticker which can be used over an extremely long period of time and therefore eliminates the necessity of removal and replacement on the occasion of each oil change or other servicing of the vehicle, which is required with the well-known single use stickers of the prior art.

Another object of my invention is to provide a sticker which can be used considerably longer than the conventional vehicle maintenance sticker.

Still another object of my invention is the provision of a vehicle maintenance sticker that will withstand weather conditions of all kinds.

A further object of my invention is to provide a vehicle maintenance sticker that can be easily revised when necessary without replacing the whole sticker.

Numerous other objects and advantages of the invention will be apparent as it is better understood from the following description, which, when taken in connection with the accompanying drawing, discloses a preferred embodiment thereof.

In the drawings:

Figure 1 shows an isometric view of one embodiment of my invention;

Fig. 2 shows a front view of the record device of Fig. 1;

Fig. 3 is a cross-sectional view taken substantially on the line 3—3 of Fig. 2;

Fig. 4 is a rear view of the device shown in Fig. 2; and

Fig. 5 is an enlarged fragmentary front view of another embodiment of my invention.

One embodiment of my invention illustrated in Figs. 1 to 4 of the drawing consists of a front wall A, a rear wall B and a record receiving means C. The front wall A is secured at its periphery to the rear wall B. The record receiving means C is in turn secured to the rear wall B and is mounted between the front wall A and the rear wall B. The front wall A has a rectangular opening therein and is provided with a column of vertically spaced designations or indicia adjacent one side of this opening. The opening affords access to the record receiving means C which preferably comprises a small individual paper pad horizontally aligned with each designation on the front wall A. Appropriate figures or other data may be written on selected pads of the record receiving means C which may be revised as to any particular designation without replacing the whole sticker. The rear wall B is provided with means for mounting the device on a car or in any particular place desired.

The front wall A consists of an upper heading portion 6, a designation strip 7 and a lower heading portion 8. As can be seen from this, a rectangular opening 9 consequently is formed in the front wall A. The upper

2

heading portion 6 and the lower heading portion 8 can be used for advertisements. The designation strip 7 is provided with individual designations or indicia such as date, mileage, etc. These designations extend the width of the designation strip 7 up to the periphery of the opening 9. The front wall A preferably is made of a suitable heavy impregnated paper in order to withstand various weather conditions and to make the sticker more durable.

10 The rectangular rear wall B also preferably is made of a heavy impregnated paper and affords a stiffness to the device to improve its durability. The rear wall B is connected to the front wall A by a plastic strip 11 which extends completely around the periphery of the rear wall B. This plastic strip, of course, tends to keep moisture from entering between the front wall A and the rear wall B, and secured by plastic strip 11, is the record receiving means C. This record receiving means comprises a plurality of small paper pads 12, each consisting of a number of superposed strips, which are mounted in the opening 9 by the plastic strip 11. These pads are made of a waterproof, grease resisting paper in order to withstand weather conditions and expected conditions of use. Pads 12 extend about half way under designation strip 7. By doing so, the inner (left-hand, viewing Fig. 2) free ends of pads 12 are kept from being torn loose by the retaining or designation strip 7 which overlies the same. The record receiving means C also has an upper pad means 13 and a lower pad means 14 which are secured by plastic strip 11 to rear wall B. Although these pad means consist of sheets of paper, they are not intended to be employed like the pads 12 but act primarily as a stiffening means for the device, thus affording greater durability. The record receiving means C is made of superposed sheets of oil skin paper or some similar waterproof, grease resisting material capable of receiving data written thereon in either ink or pencil. This device for maintaining data records is provided with an adhesive mounting means which, as shown in Fig. 4, preferably consists of an adhesive strip 15 on the back of the rear wall B with dry strips 16 and 17 at the top and bottom thereof. To cover the adhesive strip 15 initially is a protective backing 18. This backing is longer than the rear wall B, extending beyond the dry strips 16 and 17, to facilitate its removal when it is desired to mount the record maintaining device on any selected surface by means of the adhesive strip 15.

50 In the use of this device, when maintenance or other work is accomplished on a vehicle the results of which are desired to be recorded, such results or data may readily be written on the uppermost appropriate pads 12. After these figures are recorded the protective backing 18 is removed from the adhesive strip 15 by applying force between one end of the backing 18 and the adjacent dry strip 16 or 17. The device can then be mounted on the door jam of the vehicle or at any other desired position. When some particular maintenance is repeated on the vehicle, the data for that particular maintenance can be revised separately. This is done by sliding the inner free end of the top sheet of paper of the individual pad containing the data which is desired to be revised out from under the retaining strip 7 (toward the right in Fig. 2). This sheet can then be torn free from its pad and the new data can be recorded on the next unused sheet thereunder. Thus, my device provides a vehicle maintenance sticker which can be revised as to one portion alone without replacing the whole sticker. This, of course, obviates continually mounting new maintenance stickers on the vehicle every time maintenance is performed on the vehicle. By em-

ploying only one sticker, the maintenance record is more reliable. This also makes it easier to locate the latest maintenance record. Further, the construction of the sticker is such so as to withstand weather conditions and insure longer use of the sticker.

Fig. 5 illustrates another embodiment of my invention. This embodiment is of similar construction to that shown in Figs. 1 to 4, except that it employs a different front wall. The front wall 19 shown in Fig. 5 has an upper and lower heading portion similar to that illustrated by elements 6 and 8 in Fig. 2. Extending between and integral with these heading portions is a rectangularly shaped designation strip 21 which overlies the inner free ends of pads 12 in the same manner as strip 7. The designation strip 21 also is provided with a plurality of horizontally disposed designations similar to those shown on designation strip 7 illustrated in Figs. 1 and 2. Each of these designations is aligned with a corresponding horizontally disposed paper pad 12 that is secured to the plastic strip 11 at one side with the free ends of pads 12 extending about half way under designation strip 21. Integral with and extending laterally from designation strip 21 are a plurality of securing strips or dividing portions 22. The ends of securing strips 22 are secured to plastic strip 11, thus forming a rectangular opening 23 over each pad 12. As can be seen, each securing strip 22 overlies a lower marginal portion of one pad 12 and also overlies an upper marginal portion of the next lower pad 12. Further, the strips 22 can be made sufficiently wide so that the above-mentioned designations can be placed on both the designation strip 21 and the securing strips 22, thus extending completely across front wall 19. Thus, there is a binding action by the designation strip 21 on the ends of the pads 12 and a binding action by strips 22 on the upper and lower marginal edges of each pad 12. This prevents individual sheets of paper from being inadvertently removed from the pads 12 while a recording is being made or from ordinary wear and tear, yet

allows the individual sheets to be removed readily when it is desired to make a new recording.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A vehicle maintenance sticker, comprising a paper rear wall, a paper front wall having a plurality of rectangular openings therein, a paper pad interposed between said rear and front walls in registry with each of said opening and comprising a plurality of superposed rectangular strips, and means for securing the ends of said pads and the edges of said front and rear walls together, the top and bottom edges of adjacent said rectangular openings being defined by transversely extending dividing portions of said front wall.

2. A vehicle maintenance sticker according to claim 1 having individual indicia inscribed on said dividing portions of said front wall to designate different maintenance services, whereby appropriate records relating thereto may be written on adjacent said paper pads.

3. A vehicle maintenance sticker according to claim 1 wherein said transversely extending dividing portions overlie the marginal edges of adjacent said paper pads.
